Patented Feb. 8, 1972

222,951

COMBINED LITTER AND ARTICLE STOWAGE BUCKET FOR AUTOMOBILES OR THE LIKE

Freeman Stringer, 209 W. 3rd St.,
Lee's Summit, Mo. 64063

Filed Sept. 24, 1970, Ser. No. 25,182

Term of patent 14 years

Int. Cl. D7—05

U.S. Cl. D49—34

Fig. 1.

Fig. 2.

Fig. 3.

Fig. 4.

FIG. 1 is a side perspective view of a combined litter and article stowage bucket for automobiles or the like;

FIG. 2 is a perspective view of the side opposite that shown in FIG. 1;

FIG. 3 is a top plan view thereof; and

FIG. 4 is a bottom plan view thereof.

I claim:

The ornamental design for a combined litter and article stowage bucket for automobiles or the like, as shown.
